UNITED STATES PATENT OFFICE.

EDWARD EVERETT HOSMER, OF NEW YORK, N. Y.

BOUGIE.

Application filed March 16, 1921. Serial No. 452,750.

The present invention relates to certain improvements in bougies, or medical instruments, for insertion into the natural passages of the body, such as the rectal, vaginal and urethral areas, to cause their dilatation, or in order to apply medicaments therein.

Instruments of this character have long been known to the medical profession, and their value in the treatment of rectal and urethral disorders particularly has been generally recognized.

As heretofore constructed, the instrument usually is made of a single piece of solid rubber, wood or metal and has an insert portion to cause dilatation. This portion is of rounded configuration and terminates in a blunt point from which the cross sectional area progressively increases to a maximum for an instrument of a given size. In all the various forms of bougies, it has always been the practice to make the surface of the insert portion perfectly smooth. The effect produced by the smooth surface insert portion on certain passages of the body, such for example as the anal canal, will be better understood after a consideration of the anatomical structure of these parts, especially the inner walls or linings of such passages.

It is well known that some of the passages of the body, in the treatment of which the bougie is used, have an inner lining or layer of muscular convolutions approximating in form a spiral channel. The inner lining of the small and large intestines are illustrations of such a structure. When a bougie of the usual construction is introduced in such passage, as for instance the anal canal, the sphincter muscles are divided and the wall of the canal is subjected, by the insert or distending portion of the instrument, to a pressure depending upon the amount of dilatation. The pressure is applied to the projecting muscular formations and, as well, to the walls proper, at every point about the circumferential area of impingement between the smooth surface of the insert portion and the inner wall of the canal. Now, since the inner walls constitute the seat of the terminal nerve endings, these nerves are subjected, over the entire area of contact, to the full distending pressure, with the result that they are to a marked degree paralyzed and rendered incapable of proper functioning. Thus the smooth surface bougie though serving sufficiently to distend the passage, and when suitably pre-

pared, to apply medicaments, is not fully efficient for both purposes.

The bougie of the present invention overcomes the defects of the prior devices by having a distending or insert portion constructed so that when the instrument is introduced into a passage, the distending pressure is applied at distributed points, preferably along spiral lines, about the circumferential area of impingement. Thus, while the desired amount of dilatation is effected, the inner wall of the passage and consequently the terminal nerve endings are subjected to the full amount of the distending pressure, only at distributed points, and are free to function.

In obtaining this distribution of pressure, I have found it desirable to form the distending or insert portion of the bougie spirally to follow the conformation of the inner wall structure of the body passage, which not only serves to separate the convoluted projections of the inner wall, but also aids in the introduction of the instrument. Furthermore, as the greatest pressure is distributed along spiral lines, the introduction of the instrument is less disagreeable than is the case with the smooth surface instrument and the depressing effect of the latter on the terminal nerve endings is to a large extent remedied.

The distending or insert portion of the instrument may be provided with spiral ridges, or spiral depressions, or both; or, when the instrument is used without medicaments and for dilatation only, the distending or insert portion may consist of spiral wires alone. When the bougie is used for the application of medicaments, the spiral formation of the surface acts as a carrier or receptacle therefor, by which the treatment is greatly facilitated, and this is especially so with the spiral depressions.

Whether or not the surface of the distending portion of the bougie is of spiral formation, but preferably in combination with such a construction, the invention comprehends as another of its parts a bougie the distending portion of which is hollow to receive means whereby the surface of this portion of the instrument may be heated. In the preferred construction, the distending portion is hollow and the instrument has a neck opening leading to the interior of the distending portion through which a hot liquid may be introduced therein. A cap

is provided for closing the opening, which serves at the same time as a handle for the instrument.

In the preferred construction described hereinafter, the bougie has a rounded insert or distending portion provided with spiral ridges, both the ridges and the insert portion being of progressively increasing cross sectional area from the point of the instrument.

The invention is illustrated in the accompanying drawings in application, as an example, to a rectal bougie having spiral ridges on the insert portion thereof, in which Fig. 1 is a side view of the instrument; Fig. 2 is a section along the line 2—2 Fig. 1, and Fig. 3 is a modification showing a longitudinal sectional view in which the insert portion is hollow.

The instrument comprises an insert or distending portion 1 of progressively increasing cross sectional area from the point thereof. The surface of this portion is provided with spiral ridges 2, and the instrument has a handle 3. The handle is separated from the insert portion by an annular projection 4 which limits the extent to which the instrument can be introduced in the anal canal. The ridges 2 are of progressively increasing cross sectional area from the point of the instrument, and I have found that the best results are obtained by graduating the ridges from a sixty-fourth of an inch square at the point to three times that size as to height and twice the size as to breadth at the opposite end of the insert portion. Also, I have found in practice that the number of spirals on a three-quarter inch bougie should be three and the inch and large sizes four to secure the greatest amount of relief to the nerve areas from the distending pressure.

When the instrument is introduced it is given a slight turning movement only inasmuch as the spirals are of relatively high pitch, the spiral ridges engage the spiral formation of the inner walls of the passage, opening them and pressing the walls outwardly along spiral lines. Thus, while the desired amount of dilatation is caused by the outer surfaces of the ridges, the areas falling between the ridges are relieved of the direct

application of the distending pressure and consequently the nerve endings in such areas are unaffected and retain their normal vitality.

In Figure 3, the insert portion 1 is hollow, and the instrument has a threaded neck opening 6, communicating with the interior 7 of the insert portion through which hot liquid may be introduced therein to heat the surface of this portion of the instrument. The handle 3 serves as a cap to close the opening and is made to screw therein, a washer 8 being provided to secure a watertight joint.

I claim:

1. An instrument of the character described having a distending portion of rigid material, and ridges formed on said portion with their surfaces continuous with the surface of said portion, the ridges comprising a plurality of spirals of relatively high pitch extending in the general longitudinal direction of the instrument and progressively increasing in cross-sectional area as they recede from the point of the instrument.

2. An instrument of the character described having a distending portion of rigid material of bulbous form and terminating in a relatively blunt point, and ridges formed on said portion with their surfaces continuous with the surface of said portion, the ridges comprising a plurality of spirals of relatively high pitch extending in the general longitudinal direction of the instrument.

3. An instrument of the character described having a distending portion of rigid material of bulbous form and terminating in a relatively blunt point, and ridges extending from the point throughout said distending portion and formed with their surfaces continuous with the surface of said portion, the ridges comprising a plurality of spirals of relatively high pitch extending in the general longitudinal direction of the instrument and progressively increasing in cross-sectional area as they recede from the point of the instrument.

In testimony whereof I affix my signature.

EDWARD EVERETT HOSMER.
